UNITED STATES PATENT OFFICE

FULTON CUTTING, OF NEW YORK, N. Y.

ELECTROMAGNET AND VOLTAGE DIVIDER

Application filed January 9, 1928. Serial No. 245,519.

My invention relates particularly to improvements in radio broadcast receivers.

One object of my invention is to simplify the filtration of the anode current source.

Another object is to provide a more efficient 5 loud speaking telephone without requiring any appreciable amount of additional power for the operation of the receiver, thereby increasing its overall sensitivity.

Another object is to cheapen the construction 10 of the anode current filter of a radio receiver and at the same time increase the power and sensitivity of its associated loud speaking telephone.

Another object is to supply a simple and reliable 15 source of grid biasing voltage.

Referring to the drawings, Fig. 1 shows a typical receiver employing two stages of 20 tuned radio frequency amplification, a detector and two stages of transformer coupled audio frequency amplification, although it should be understood that I do not care to limit my invention to use with any particular form of radio receiver.

Fig. 2 shows the field winding of an electro-dynamic speaker similar to that illustrated as part of Fig. 1 but with an additional tap to provide negative grid bias or "C" voltage.

In Fig. 1, the first and second stages of radio frequency amplification are shown at 1 and 2 respectively, the detector and its associated circuits at 3, the first stage of audio frequency amplification at 4 and the second stage 35 at 5, this latter stage preferably employing a power tube at 6 and a grid biasing battery 7.

A loud speaking telephone of the electro-dynamic type is diagrammatically indicated at 8. 9 indicates the field core and 10 the field 40 winding. This winding for the reasons hereinafter set forth should have a much greater number of turns than the conventional type design for operation at cathode heating voltages. 11 represents the moving coil, 12 a diaphragm of any suitable type.

A condenser 13 of suitable value may be placed across the input leads of the field winding, which, as indicated in the drawing, are connected to the anode source +B, -B 45 which may preferably be commercial direct

current or rectified commercial alternating current.

The winding 10 is so proportioned as to give the proper field with whatever maximum voltage is chosen for the anode source. The anode voltage for the last audio frequency stage 5 is tapped off from the winding 10 at the point 14 and the condenser 15 provides the alternating current return. The anode voltage for the audio frequency stage 4 and the radio frequency stages 1 and 2 may be tapped off from the point 16 and the condenser 17 provides the alternating current return for these three stages. The detector anode voltage may be tapped off from the point 18 and the alternating current return 55 provided by the condenser 19.

It will be seen that by proper arrangement of taps the desired anode voltage may be applied to any tube or group of tubes. The field winding constitutes the inductive part of a typical inductance-capacity filter. It is the usual practice to run the radio frequency tubes on a moderate anode voltage, the detector at a low anode voltage and the last audio 70 frequency or output tube at a high voltage. An alternating current component in the anode voltage is most disastrous in the detector tube, less so in the first audio frequency amplifier and still less so in the output tube, the 75 reason, of course, being that any alternating current component in the detector tube is amplified twice before being reproduced in the loud speaking telephone, and any fluctuations in the anode voltage in the first audio 80 frequency amplifier is amplified once before being reproduced.

It will be seen that according to my invention the amount of filter inductance is greatest for the detector, least for the output 85 tube, and a value of inductance between these two points may be chosen for the first audio frequency amplifier, which, as above set forth is the proper relation. Thus, it will be seen that the appropriate voltages 90 and the appropriate amount of filter inductances may be said to go hand in hand in my invention.

Fig. 2 is a modification of the field winding shown at 10 in Fig. 1 so arranged as to 100

provide not only various filtered anode voltages but also to provide grid biasing or "C" voltage.

The core 9 carries the field winding 10' having the taps 14', 16', 18', 20 and 21. Filter condensers, such as, 15, 17, 19, Fig. 1, may be provided. The tap 14' may provide anode voltage for the output tube or "power amplifier." The tap 16' may supply a somewhat lower voltage to the amplifier tubes, and the tap 18' a still lower voltage to the detector anode supply.

The point 20 is connected to the filament circuit at a suitable point and the voltage drop between this point and the point 21 is used to supply grid bias or "C" voltage to such tubes as desired.

By means of my invention a very much more efficient and powerful loud speaker may be provided with very little addition to the cost of the anode supply filter alone.

It should be understood that I do not wish to limit myself to the specific form shown in the specification, only in so far as I am limited by such claims as may be allowed.

I claim:

1. In combination with a radio receiver having vacuum tubes and an anode power source, an electro-dynamic loud speaking telephone having a field winding, said winding having taps and being connected to said anode source, said taps being connected to the anodes of the various tubes.

2. In combination, a radio receiver having valves each with at least three electrodes, an anode power source, and a loud speaker having a field winding having taps, and being connected to said anode power source said taps being connected to the anodes of various of said valves, said taps being so spaced apart as to supply the desired voltages to said various valves and said winding acting as a filter inductance for said anode power source.

3. A radio receiving system having electronic relays arranged for radio frequency amplification, detection, and audio frequency amplification and an electrodynamic speaker having coil windings tapped appropriately to serve as a voltage divider for the plate anode circuits of said various relays.

4. In combination, a power supply, an electro-dynamic loud speaker with a field winding having taps, substantially all of said winding being connected across said power supply, one part of said winding functioning as a voltage divider to supply anode voltages of differing magnitudes to various of the vacuum tubes of a radio receiver, another part of said winding being used to supply grid biasing voltage to certain of said vacuum tubes, said winding acting as a filter inductor for said supplied voltages.

5. A radio receiver having vacuum tubes, an anode supply source for said tubes, a loud

speaker having tapped field windings, means of connection between said windings and the anode supply source for energizing the magnetic field of said speaker, means of connection between the taps of said windings and the receiver so that the windings function as a filter inductor for the receiver, and at the same time deliver appropriate voltages to the various anode circuits of said receiver.
